UNITED STATES PATENT OFFICE.

JOHN R. HAMILTON, OF YONKERS, NEW YORK.

CHEMICAL FIRE-EXTINGUISHING APPARATUS.

1,388,998.

Specification of Letters Patent. Patented Aug. 30, 1921.

Application filed November 16, 1916. Serial No. 131,629.

To all whom it may concern:

Be it known that I, JOHN R. HAMILTON, a citizen of the United States, and resident of Yonkers, Westchester county, New York, have made certain new and useful Invention 5 relating to Chemical Fire-Extinguishing Apparatus, of which the following is a specification, taken in connection with the accompanying drawing, which forms part of the 10 same.

The invention described in this application, which is a partial continuation of, that is, contains subject-matter taken from my pending application, Serial Number 813,372, 15 filed January 21, 1914, relates especially to chemical fire extinguishing apparatus in which the distributing system which may be of the dry pipe type is under fire emergency conditions supplied with extinguishing 20 liquid by the operation of a connected chemical pressure tank. This tank may be provided with mixing devices comprising a chamber containing sulfuric acid or other pressure producing chemical and a connected siphon may be automatically operated to 25 discharge and render effective the chemical through the action of the fluid pressure changes caused during the emergency operation of the system. For this purpose any 30 suitable arrangement of pipes or operating connections may be used communicating with the distributing system and the siphon for discharging the acid or other pressure producing liquid, so as to automatically operate 35 the siphon when one of the automatic sprinkler heads or other extinguishing devices comes into operation.

In the accompanying drawings showing in a somewhat diagrammatic way illustrative 40 embodiments of this invention—

Figure 1 is a sectional elevation of one form of the invention as applied to a dry pipe system.

Fig. 2 is an enlarged detail section thereof.

Fig. 3 is a sectional elevation showing another embodiment.

Fig. 4 shows another embodiment in sectional elevation; and

Fig. 5 shows in sectional elevation another embodiment of the invention as applied to a wet pipe system.

The distributing system may be of any suitable form and may comprise one or more supply pipes or risers 1 and connected distributing pipes, such as 2, shown in Fig. 1,

on which any suitable distributing devices, such as automatic sprinkler heads 3, may be mounted at various points. Suitable hose connections, such as 5, may be arranged at various parts of the distributing system so as to operate connected hose lines when the valves 4 are open. The distributing system which is preferably though not necessarily of the dry pipe type, may be connected in any suitable way with the chemical pressure liquid supply tank 8, as for instance, by the depending tank connection having if desired a flaring lower end 7 adjacent the bottom of the tank protected by a suitable screen 6. There may also be arranged a suitable equalizing connection or aperture communicating with the air space of the tank to take care of temperature expansion and other slight pressure variations, and for this purpose the equalizing aperture 23 may be formed adjacent the top of the tank connection.

The liquid supply tank 8 of any suitable shape and construction is normally filled to the desired extent with extinguishing liquid 13 which may comprise suitable carbonate material dissolved for instance throughout the liquid and with which the sulfuric or other acid is adapted to coöperate under emergency conditions to quickly generate the desired high pressure by chemical action and force the extinguishing liquid out of the tank into the distributing system to be discharged therefrom at high working pressure. The mixing devices used for effecting the mixture of these chemicals may comprise an acid chamber, an acid discharging siphon coöperating therewith and an air or pressure chamber communicating in any desired way with the acid chamber so as to cause sufficient pressure difference under emergency conditions to start the siphon. It is sometimes advantageous to have a removable casing of any suitable construction, such as 21, mounted in the upper portion of the chemical tank 100 to support the acid chamber and allow for its convenient removal for recharging, etc. This casing may as indicated be secured as by the bolts 20 to the projecting flange 11 of the tank and may support in any suitable way the acid chamber 15 so as to preferably although not necessarily have the normal acid level considerably above the liquid level in the tank, it being of course understood that the acid containing portion of 110

the chamber may be formed of lead or other acid resisting material. The acid discharging siphon which may be formed in whole or in part of similar acid resisting material 5 may be arranged to coöperate in any suitable way with the acid chamber and tank and may, if desired, be provided with an admission leg, such as 14, extending considerably above the normal acid level in the acid 10 tank so as to minimize undesirable action by requiring a rise of a considerable portion of a foot at least before the acid reaches the top of the siphon. The discharge leg of the siphon may be arranged substantially 15 in line with the acid chamber in any desired way and may with advantage be arranged to be removed through the hole in the flange to which the casing is secured. This discharge leg may sometimes though not necessarily 20 be extended considerably below the liquid level in the tank so that its discharge end 22 may extend a foot or two below in some cases, and when the extinguishing liquid is discharged from the tank during emergency 25 conditions the acid discharge tends to increase so as to make the working pressure increase gradually as is desirable in many cases. If desired the communicating air 30 chamber may be formed in the upper part of the removable casing 21 so as to directly communicate with the acid chamber and be a substantial continuation thereof.

An air connection of any suitable form is also preferably provided between the air 35 chamber and the air space in the tank above the liquid therein. It is also desirable to provide a suitable check valve coöperating with the air connection so as to insure the reliable starting of the siphon action and so as to 40 thereafter insure under emergency conditions a large area passage into the air chamber and promote the continuation of the siphon action. In order to minimize the 45 chance of the siphon action being started by accidental temperature expansion or other gradual pressure changes during the normal condition of the system, it is also desirable to have a small area compensating passage between the air chamber and air space of the 50 tank which may, if desired, be combined with the check valve. If desired, the air connection 17 communicating with the air chamber 9 as shown in Figs. 1 and 2 may be arranged within the removable casing 21 and 55 may have a suitable check valve, such as 18, arranged adjacent its lower portion for more convenient cleaning and inspection when the casing is removed, so that when the emergency siphon action has been started and the 60 chemically generated pressure increases in the tank this check valve is free to rise toward the separated guiding ribs or projections 16 so as to give a large area opening through this air connection into the pressure 65 chamber above the acid, so that the air pres-

sure both above and below the acid are thus substantially equalized allowing the siphon discharge of the acid into the carbonate material to continue. This check valve may be conveniently formed with a pin hole or 70 small area equalizing passage 19 therethrough so as to allow the gradual equalizing flow of air in either direction between the air chamber and the air tank, this equalizing passage being preferably, however, considerably smaller than the equalizing aperture 23 or other means of relieving the air pressure in the tank under emergency conditions so that this equalizing passage does not interfere with the emergency starting of the 80 siphon.

In the illustrative embodiment of the invention shown in Fig. 3, the chemical pressure tank 8 may contain similar carbonate extinguishing liquid 13 so as to supply the 85 connected riser 1 and other parts of the distributing system under fire emergency conditions. The chemical mixing devices may in this instance comprise the casing 24 having the removable cover 25 and secured to the 90 tank above the aperture 29 therein, so that the bottom 34 of this casing supports the acid chamber 27 of suitable material inert to the sulfuric acid or other pressure producing 95 chemical 28 contained in this chamber. The chemical discharging siphon 26 may be arranged to coöperate with this acid chamber into which its admission leg may dip and its discharge leg may extend down through the casing bottom so as to communicate with the 100 chemical tank below, it being in some cases advantageous to have the end of this discharge leg of the siphon somewhat above the normal level of the carbonate liquid in the tank. The coöperating air chamber may be 105 separately mounted, the air chamber 30 being, if desired, bolted to the tank 8, while it is connected to the casing 24 by the connection 34 which under fire emergency conditions assists in exerting sufficient unbalanced pressure on the top of the acid or 110 chemical 28 to automatically cause the discharging action of the siphon. A check valve, such as 32, may be mounted to control the opening between the air chamber and tank so that under some conditions this check 115 valve may rise toward the guide ribs or projections 31 and a pin hole or equalizing passage 33 may be arranged anywhere so as to equalize the gradual expansion changes in 120 pressure between the tank and air chamber, and if desired the pin hole equalizing passage 33 may be arranged in the check valve 32 as indicated.

In the illustrative embodiment shown in 125 Fig. 4, the distributing system may be connected to a similar chemical pressure tank 8 containing carbonate extinguishing liquid 13, and a casing or air chamber 35 preferably having the large sized body and reduced neck 130

65 may be bolted or otherwise secured to the tank. The acid or chemical chamber 36 may be supported in any convenient way, as for instance, by being mounted within this air 5 chamber 35 so that the coöperating discharging siphon 37 having its admission leg dipping within the sulfuric acid or other pressure producing chemical 28 may discharge the same into the tank under emergency conditions. To effect this action the discharge 10 end of the siphon may be formed with an enlargement or bell 38 normally containing liquid and preferably located within the neck 65 so that a reduced annular or other shaped 15 passage 62 for the discharge of liquid is formed around this bell. Under fire emergency conditions some of the distributing devices open and allow the moderate air or other pressure in the distributing system to 20 escape quickly so that the unbalanced air pressure in the large volume air chamber acts to discharge therefrom the carbonate liquid which may advantageously extend up to about the top of the enlarged discharge 25 end 38 of the siphon. In this way the liquid level is lowered in the neck 65 so that the liquid within the siphon end is left unsupported and acts to suck the chemical 28 up into its admission end so that the discharging 30 action of the siphon is quickly started because of the large volume discharge of liquid from its lower end. By locating the lower end of this discharge leg of the siphon within the small area neck 65 the liquid 35 descends in this neck so rapidly, under emergency conditions that when the acid is discharged from the siphon its lower end is practically or entirely free from surrounding liquid so that the clear discharge of the 40 acid can be insured. This action may be promoted by forming a suitable enlargement or equalizing chamber 41 in the distributing system having its bottom at about the normal liquid level therein when the system is 45 inoperative, so that under emergency conditions the first flow of liquid fills this chamber and does not cause during this time any very great increase of static pressure. If desired, the slow temperature changes in 50 pressure in the air chamber and distributing system may be equalized through a suitable equalizing connection 39 which may be provided with the diaphragm 40 formed with the pin hole or reduced equalizing 55 aperture 64 which is not of course sufficient to allow any undesirable or substantial flow under emergency conditions.

In the illustrative embodiment shown in Fig. 5, the invention is illustrated as applied to a wet pipe distributing system comprising distributing lines 2 on which suitable distributing devices, such as the sprinkler heads 3, are arranged at suitable points throughout the building. This distributing system may 60 be connected through the tank connection 7 with a supplemental supply of extinguishing liquid such as the chemical pressure tank 8 containing carbonate extinguishing liquid 13, for instance. The coöperating chemical mixing devices may comprise an air chamber or dome 42 removably connected, if desired, with a coöperating acid chamber 66, so that the connected reduced area neck 60 may be removably bolted or otherwise connected to the tank 8. The sulfuric acid or 70 other pressure producing chemical 28 in this acid chamber 66 may be discharged therefrom under fire emergency conditions by the discharging siphon 52 which may have its admission end dipping into the 75 liquid adjacent the bottom of this acid chamber while its lower discharge end communicates with the neck within a small volume enlargement or discharge chamber 59 communicating with the tank so as to form 80 the air space thereof. An equalizing air connection 43 may communicate with the air chamber 42 and have its lower end communicating with the neck or other adjacent 85 parts of the device below the normal level 90 of the liquid therein, so that the liquid forms a valve or seal in this pipe and a liquid sealed air equalizing connection is thus provided which is normally closed but which when the mixing devices come into emergency 95 operation is automatically opened to allow free equalization of the pressures above and below the discharging siphon. Sufficient air pressure is maintained in the 100 air chamber or adjacent parts to normally 105 maintain the distributing liquid of any suitable character in the distributing system and for this purpose a suitable pressure pump or device 51 may be connected through the air pipe 63 and check valve 50 with the equalizing air pipes 47, 45 communicating with the air chamber 42 and also if desired with the supplemental reduced volume chamber 59. If desired, this air pipe 45 may also serve 110 as an equalizing connection between the chambers 42 and 59 and for this purpose the pin hole or other small area equalizing aperture 46 may be interposed at any point in this pipe. In order to compensate for slight leakage of liquid from the system it is desirable to have a priming tank 48 preferably of large area connected with the chemical tank or communicating neck 60 preferably through the connection 53 having the relatively small area passage or aperture 49 115 120 therein. The air space of this priming tank may be connected as by the air pipe 47 with the chamber 59 so that in case of leakage the normal liquid level in the neck is not substantially lowered. It is also desirable to 125 form a suitable chamber, such as 44, communicating with the equalizing air connection 43 so that when the system is filled with liquid or the air pressure applied thereto any undesirable flow of liquid up through 130

the pipe 43 will tend to pass into the chamber 44 so as to minimize the possibility of this liquid entering the acid chamber 66.

Under fire emergency conditions when one of the sprinkler heads or other distributing devices operates the air pressure in the chambers 42, 59 causes this discharge of the liquid from the distributing device and also forces the liquid down in the neck 60 at the same time starting the discharging siphon 52. When this siphon has started the liquid is rapidly forced out of that part of the neck with which the equalizing connection 43 communicates so that this connection is thus opened and allows the continued discharge of the siphon until substantially all of the acid is discharged into the mixing tank below to cause the desired chemically generated high pressure effecting the continued discharge of the operating distributing device.

This invention has been described in connection with a number of illustrative embodiments, forms, proportions, parts, arrangement, materials, methods of use and connection, to the details of which disclosure the invention is not of course to be limited, since what is claimed as new and what is desired to be secured by Letters Patent is set forth in the appended claims:

1. In chemical fire extinguishing apparatus, a wet pipe distributing system comprising distributing devices including automatic sprinkler heads, a connected gaseous pressure liquid supply tank charged with carbonate extinguishing liquid and coöperating chemical mixing devices comprising a chamber containing a charge of acid pressure producing chemical, a discharge siphon communicating with said chamber to discharge said chemical into said tank, an air chamber communicating with said acid chamber, a neck normally containing liquid and constituting a passage between said tank and the discharge end of said siphon, a small volume discharge chamber formed in said neck around the discharge end of said siphon, an equalizing air connection between said air chamber and said neck below the normal liquid level therein and formed with an upwardly extending chamber above said liquid level to constitute a liquid sealed equalizing air connection, a large area priming tank communicating with said neck and a small area equalizing passage normally open between said air chamber and the upper part of said neck.

2. In chemical fire extinguishing apparatus, a wet pipe distributing system comprising distributing devices, a connected gaseous pressure liquid supply tank charged with carbonate extinguishing liquid and coöperating chemical mixing devices comprising a chamber containing a charge of acid pressure producing chemical, a discharge siphon

communicating with said chamber to discharge said chemical into said tank, an air chamber communicating with said acid chamber, a neck normally containing liquid and constituting a passage between said tank and the discharge end of said siphon, an equalizing air connection between said air chamber and said neck below the normal liquid level therein to constitute a liquid sealed equalizing air connection, a large area priming tank communicating with said neck, and a small area equalizing passage normally open between said air chamber and the discharge end of said siphon.

3. In chemical fire extinguishing apparatus, a wet pipe distributing system comprising distributing devices, a connected gaseous pressure liquid supply tank charged with carbonate extinguishing liquid and coöperating chemical mixing devices comprising a chamber containing a charge of acid pressure producing chemical, a discharge siphon communicating with said chamber to discharge said chemical into said tank, an air chamber communicating with said acid chamber, a neck normally containing liquid and constituting a passage between said tank and the discharge end of said siphon to effect the operation of said discharge siphon when liquid recedes from said neck during the fire emergency condition of said apparatus and a small area equalizing passage normally open between said air chamber and the discharge end of said siphon.

4. In chemical fire extinguishing apparatus, a wet pipe distributing system comprising automatic distributing devices, a connected gaseous pressure tank and coöperating chemical mixing devices comprising a chamber containing a charge of pressure producing chemical, a discharge siphon communicating with said chamber to discharge said chemical into said tank, an air chamber communicating with said chemical chamber, a neck normally containing liquid and constituting a passage between said tank and the discharge end of said siphon, a small volume discharge chamber formed in said neck around the discharge end of said siphon, a small area equalizing passage normally open between said air chamber and the discharge end of said siphon, and a fluid pressure device communicating with said air chamber to create sufficient pressure therein to normally maintain liquid in said distributing system.

5. In chemical fire extinguishing apparatus, a wet pipe distributing system comprising automatic distributing devices, a connected gaseous pressure tank and coöperating chemical mixing devices comprising a chamber containing a charge of pressure producing chemical, a discharge siphon communicating with said chamber to discharge said chemical into said tank, an air chamber

communicating with said chemical chamber, a neck normally containing liquid and constituting a passage between said tank and the discharge end of said siphon to effect the 5 operation of said discharge siphon when liquid recedes from said neck during the fire emergency condition of said apparatus, a small area equalizing passage between said air chamber and the discharge end of said 10 siphon, and a fluid pressure device.

6. In chemical fire extinguishing apparatus, a distributing system comprising distributing devices, a connected gaseous pressure tank and coöperating chemical mixing devices comprising a chamber containing a charge of pressure producing chemical, a discharge siphon communicating with said chamber to discharge said chemical into said tank, an air chamber communicating with 15 said chemical chamber, a neck normally containing liquid and constituting a passage between said tank and the discharge end of said siphon to effect the operation of 20 said discharge siphon when liquid recedes from said neck during the fire emergency condition of said apparatus, and an equalizing passage between said air chamber and 25 the discharge end of said siphon.

7. In chemical fire extinguishing apparatus, a wet pipe distributing system comprising distributing devices, a connected gaseous pressure liquid supply tank charged with carbonate liquid and co-operating chemical mixing devices comprising a chamber containing a charge of acid pressure producing chemical, a discharge siphon communicating with said chamber to discharge said chemical into said tank, an air chamber communicating with said acid chamber, a neck normally containing liquid and constituting a passage between said tank and the discharge end of said siphon, an equalizing air connection between said air chamber and said neck below the normal liquid level therein and formed with an upwardly extending chamber above said liquid level to constitute a liquid sealed equalizing air connection, a large area priming tank communicating with said neck, a small area equalizing passage normally open and communicating with said air chamber, and a fluid pressure device communicating with said air chamber to create sufficient pressure therein to normally maintain liquid in said distributing system.

8. In chemical fire extinguishing apparatus, a wet pipe distributing system comprising distributing devices, a connected gaseous pressure tank charged with carbon-
60 ate liquid and coöperating chemical mixing devices comprising a chamber containing a charge of acid pressure producing chemical, a discharge siphon communicating with said chamber to discharge said chemical into said tank, an air chamber communi-
65

cating with said acid chamber, a neck normally containing liquid and constituting a passage between said tank and the discharge end of said siphon, an equalizing air connection between said air chamber and said neck 70 below the normal liquid level therein to constitute a liquid sealed equalizing air connection, a small area equalizing passage normally open and communicating with said air chamber, and a fluid pressure device to 75 create sufficient pressure therein to normally maintain liquid in said distributing system.

9. In chemical fire extinguishing apparatus, a wet pipe distributing system comprising distributing devices, a connected gaseous pressure tank charged with carbonate liquid and coöperating chemical mixing devices comprising a chamber containing a charge of acid pressure producing chemical, a discharge siphon communicating with said chamber to discharge said chemical into said tank, a neck normally containing liquid and constituting a passage between said tank and the discharge end of said siphon to effect the operation of said discharge siphon when liquid recedes from said neck during the fire emergency condition of said apparatus, and an equalizing air connection between said air chamber and said neck below the normal liquid level therein to constitute a liquid sealed equalizing air connection.

10. In chemical fire extinguishing apparatus, a distributing system comprising distributing devices, a connected gaseous pressure tank and coöperating chemical mixing devices comprising a chamber containing a charge of pressure producing chemical, a siphon discharge device communicating with said chamber to discharge said chemical into said tank, a neck normally containing liquid and constituting a passage between said tank and the discharge end of said siphon discharge device, an equalizing air connection between said air chamber and said neck below the normal liquid level therein to constitute a liquid sealed equalizing air connection, a large area priming tank and a restricted priming passage communicating with said priming tank and said neck. 110 115

115
11. In chemical fire extinguishing apparatus, a distributing system comprising distributing devices, a connected gaseous pressure and coöperating chemical mixing devices comprising a chamber containing a charge of pressure producing chemical, a discharge device communicating with said chamber to discharge said chemical into said tank, a neck normally containing liquid and constituting a passage between said tank and the discharge end of said discharge device, a priming tank, and a priming passage communicating with said priming tank and said neck. 120

- ratus, a distributing system comprising automatic distributing devices, a gaseous pressure liquid supply tank charged with carbonate extinguishing liquid and coöperating 50 in said connections.
- 5 chemical mixing devices comprising a chamber containing a charge of acid pressure producing chemical, a discharge siphon communicating with said chamber and connections coöperating with said tank and said siphon 55
- 10 to automatically start said siphon on the emergency action of one of said distributing devices.
13. In chemical fire extinguishing apparatus, a distributing system comprising automatic distributing devices, a gaseous pressure tank and coöperating chemical mixing devices comprising a charge of liquid pressure producing chemical and a coöperating discharge siphon, and connections coöperating 60 with said tank and said siphon and controlled by the fluid pressure conditions in said distributing system to automatically start said siphon on the emergency action of the distributing devices.
14. In chemical fire extinguishing apparatus, a distributing system comprising automatic distributing devices, a liquid supply tank charged with extinguishing liquid and coöperating chemical mixing devices comprising a chamber containing a charge of pressure producing chemical, a discharge siphon communicating with said chamber and connections coöperating with said tank and said siphon to automatically start said siphon 65 on the emergency action of one of said distributing devices without requiring the movement of any rigid element.
15. In chemical fire extinguishing apparatus, a distributing system comprising automatic distributing devices, a gaseous pressure tank and coöperating chemical mixing devices comprising a charge of liquid pressure producing chemical and a coöperating discharge siphon, and connections coöperating 70 with said tank and said siphon controlled by the fluid pressure conditions in said distributing system to automatically start said siphon on the emergency action of one of the 75

16. In chemical fire extinguishing apparatus, a distributing system comprising distributing devices, a pressure liquid supply tank charged with extinguishing liquid containing carbonate material and chemical mixing devices comprising an acid chamber, a communicating air pressure chamber, an acid discharge siphon communicating with said acid chamber and with said tank, and a liquid sealed air connection between said air chamber and the air space of said tank. 85
17. In chemical fire extinguishing apparatus, a distributing system comprising distributing devices, a liquid supply tank charged with carbonate extinguishing liquid and chemical mixing devices coöperating with said supply tank and comprising a chemical chamber containing a charge of acid pressure producing chemical and having a normally closed air space above said chemical, a discharge siphon communicating with said chemical chamber and connections between said system, said tank and said chamber to automatically start said siphon and discharge said chemical to said tank on the emergency condition of said system. 90
18. In chemical fire extinguishing apparatus, a distributing system comprising distributing devices, a liquid supply tank charged with extinguishing liquid and chemical mixing devices coöperating with said supply tank and comprising a chemical chamber containing a charge of pressure producing chemical, an air chamber communicating with the space above said chemical, a discharge siphon communicating with said chemical chamber and connections between said system, said tank and said chamber to automatically start said siphon on the emergency condition of said system. 95
